DESIGN FOR A MAGAZINE CHEST

Solomon Laikind, Detroit, Mich.

Application June 26, 1935, Serial No. 57,419

Term of patent 7 years

To all whom it may concern:

Be it known that I, Solomon Laikind, a citizen of the Union of Socialist Soviet Republics, residing at Detroit, in the county of Wayne and State of Michigan, have invented a new, original, and ornamental Design for a Magazine Chest, of which the following is a specification, reference being had to the accompanying drawing, forming a part thereof, in which,

Fig. 4 is a central longitudinal vertical sectional view thereof.

I claim:

The ornamental design for a magazine chest, as shown and described.

SOLOMON LAIKIND.
